UNITED STATES PATENT OFFICE.

JULIUS J. GRUENFELD, JR., OF CHICAGO, ILLINOIS.

SOFA-BED.

1,379,300.

Specification of Letters Patent. Patented May 24, 1921.

Application filed February 5, 1917. Serial No. 146,596.

To all whom it may concern:

Be it known that I, JULIUS J. GRUENFELD, Jr., a citizen of the United States, and a resident of Chicago, in the county of Cook and State of Illinois, have invented certain new and useful Improvements in Sofa-Beds, of which the following is a full, clear and exact description.

The invention relates to sofa beds.

One object of the invention is to provide an improved construction for a folding sofa bed comprising a section of the bed which is folded into position at the back of the sofa, a section fixed to an overturning seat and a plurality of sections below the seat when the bed is closed.

A further object of the invention is to provide an improved sofa bed composed of foldably connected sections, one of which is adapted to be folded to a position at the back of the sofa and is provided with a sofa back pivoted thereto and is foldable to a pendant position at the front of the bed when the latter is in operative position.

A further object of the invention is to provide an improved sofa bed which may be easily operated from closed to open position and vice versa.

Other objects of the invention will appear from the detailed description.

The invention consists in the several novel features hereinafter set forth and more particularly defined by claims at the conclusion hereof.

In the drawings: Figure 1 is a vertical transverse section of a sofa-bed embodying the invention, the bed being closed. Fig. 2 is a detail perspective of the locking joint between the foot-section of the bed and the section fixed to the overturning seat, the parts being shown in position assumed when the bed is closed. Fig. 3 is a perspective of the same, the parts being shown in position assumed when the bed is open and the lock is operative. Fig. 4 is a vertical transverse section showing the parts in position assumed during a folding operation. Fig. 5 is a vertical transverse section, showing the bed open. Fig. 6 is a partial plan of the parts in position shown in Fig. 5. Fig. 7 is a side elevation of a portion of the bed and the sofa back when the bed is closed. Fig. 8 is a rear view of the parts shown in Fig. 7. Fig. 9 is a section taken on line 9—9 of Fig. 7. Fig. 10 is a detail of one of the plates of the compound pivotal connection between the bed and the sofa frame.

The sofa frame comprises members at the sides thereof respectively, each member comprising a side 14, a front post 15, a rear post 16 and an arm rest 17. Said members are rigidly cross-connected by a board 18 at the back and top of said members and a frame 19. A seat frame carrying a seat 24 and comprising sides 20 and longitudinal connecting members 21, 22 and 23, is pivotally mounted in the sofa frame, as hereinafter set forth, and is adapted to be overturned.

A compound pivotal connection is provided between the seat-frame and the sofa frame of the type more particularly set forth in an application filed by me Sept. 13, 1916, Serial No. 119,817, whereby the seat will successively swing about different fulcra to attain the advantages more fully pointed out in said application. In the present invention, this connection comprises a pair of like plates 25 fixedly secured to the sides 14 of the sofa frame respectively. Each plate guides a lower pivot stud 26 and an upper stud 27 (Fig. 1), both fixed to a bar 28. Bars 28 are secured to the sides 20 of the seat frame respectively. Each plate 25 is provided with an arcuate slot 29 in which one of the studs 27 moves, while the seat frame is swinging around studs 26 as a fulcrum and an arcuate slot 30 in which one of the studs 26 moves when the studs 27 are positioned at the lower ends of slots 29 and are acting as a fulcrum for the seat. As a result of this construction of these plates, the seat and parts connected thereto will be caused to swing in succession about differently disposed fulcrum points, so that the seat frame will be moved forwardly without providing sliding connections for that purpose. In operation, assuming the seat to be in operative position, initial forward and upward swing of the seat will cause the studs 27 to move forwardly and downwardly in the slots 29 and until studs 27 rest in the lower ends thereof and thereafter continued

forward and downward swing of the seat will cause the studs 26 to move upwardly in the slots 30 until arrested by the upper ends thereof. In the present invention, these 5 plates 25 are cut away or open between the upper ends of the arcuate slots 29 and 30. The plates are provided with overhanging portions 31 to lock the studs against upward movement when the seat is either in its operative or completely overturned position. By forming the plate open between the overhanging portions 31, the seat can be easily manipulated to disconnect it from the studs as well as to permit placement thereof in 15 position.

The bed is composed of a section 35, which is rigidly secured to the underside of the seat frame, so that when the seat is overturned, said member will be disposed above the seat, 20 a foot section 37, which is pivoted to section 35 at 37', a short section 36, pivoted to section 35 at 36', and a head section 33 pivotally connected to the member 36. Each of these members comprises a bar at each side 25 of the bed. The sides of the head-member 33 are connected by a cross or head rail 38 and the sides of member 37 are connected by a cross or foot rail 39. A tubular bar 35^a additionally secures section 35 to the seat 30 frame. The bed frame is usually provided with a spring bottom (not shown) as well understood in the art and when the seat is overturned and the bed is in operative position, the sections of the bed frame will be 35 extended in a horizontal plane as illustrated in Fig. 5. When the bed is not in use, the foot section 37 assumes a nearly upright position to the rear of the seat and the sofa back 41; section 35 which is fixed to the seat 40 will be disposed thereunder; short-section 36 will extend vertically and downwardly from the front portion of the seat and the head-section 33 will extend rearwardly and horizontally from the lower end of section 36.

45 A sofa back 41 is pivotally connected by hinges 42 to the rail 39 and comprises a frame 43 which forms a support for a back-cushion. The purpose of connecting the sofa back to the foldable bed frame is to utilize said 50 back as means for operating the foot section in folding and unfolding the bed and as means for operating legs for supporting the bed when it is open. When the bed is open, the sofa back will be disposed below the foot 55 of the bed and the legs operated by the sofa back will support the foot of the bed when it is open, as illustrated in Fig. 5. At each side of the bed there is a leg 44, which is pivoted as at 45 to a plate 46, which is 60 secured to one end of the sofa back and a link 47 which is pivoted, as at 48, to a leg 44 and to the bed section 37, as at 49. Each plate 46 is provided with an arcuate slot 50 for the travel of stud 51 on one of the legs

44 to limit the pivotal movement of said 65 member. These slots are arranged and formed so that when the jointed leg is in operative position (Fig. 5), they will hold legs 44 against movement in that direction in which the load tends to move it. When the 70 bed is closed, as illustrated in Fig. 1, the top of the sofa back frame 43 will be disposed rearwardly of a strip or molding forming a stop 53 on the bar 18. A hand-opening is formed in the lower portion of the frame 43. 75 In opening the bed, initial pull upon the lower portion of the sofa back will cause said back to move pivotally on hinges 42 until links 47 swing legs 44 and studs 51 are arrested by the upper ends of slots 50 and 80 thereafter back 41 will cause the bed-section 37 to move in unison with said back.

A foot board 55 is pivoted, as at 56, to lugs 57 on the foot rail 39. This foot board is normally and yieldingly held in folded position across the back of bed-section 37 (Fig. 7) by springs 58, and the movement of this foot board is utilized to operate locking plates 59 which are slidably connected to the side bars of said section respectively by 90 stud-and-slot-connections 60 and are connected to the foot-board by links 61, to lock sections 37 and 35 in alined relation.

Springs 58 are connected to bed-section 37 and to the foot board 55, as at 58', so that 95 the springs will cross the dead center, so that they will serve to yieldingly hold the foot board in either of its alternative positions. When the foot board is lowered, it will press against the mattress and serve to 100 hold it on the bed which is necessary when the bed is closed, because section 37 and that portion of the mattress which is on it are then vertically disposed. Springs 68 are connected to bed-section 33, as at 69, and to 105 the sofa frame, as at 70, and serve to hold up the head-section of the bed when the latter is closed, as shown in Fig. 1 and to hold said member downward and alined with the remaining sections of the bed when the latter is open, as shown in Fig. 5, the connector for these springs being disposed so that 110 they will operate in this manner. These springs, while the seat is being overturned, exert a pull upon the head section 33 in such 115 direction that they will tend to aline the sections 33 and 36 so that no separate shift of these sections will be necessary. In closing the bed, these springs 68 retard the movement of sections 33, 36, so they will pass into 120 position shown in Fig. 1, without special operation. The pivotal connections between sections 35 and 36 and between sections 36 and 33 are suitably formed to limit relative closing movement to the position shown, to 125 leave a space for the mattress and bed clothes.

The pivotal connections between the bed-

sections are formed to stop relative movement thereof so they cannot swing beyond aligned position in opening the bed. A base-board 63 is pivotally connected to the seat-frame 20, as at 64, and when the bed is closed, this board will serve as a closure for the front of the sofa below the seat. Springs 65 are connected to the sofa frame, as at 66, and to the board 63, as at 67, to exert a rearward pull on the board at all times, so that it will be seated against the front of the seat frame when the bed is closed, and so that the board will swing rearwardly when the seat is being overturned in opening the bed. These springs thus serve to pull the board 63 backwardly when the bed is unfolded and the seat is overturned, without necessitating a separate movement or operation to shift said board. Springs 65 are connected to the board 63, as at 67, to the frame 16, as at 66, and serve to exert a backward pull upon the footboard to cause said board to control the movement of the link section 36 when the seat is in overturned position.

The operation of the sofa bed will be as follows: Assuming the bed be closed, as shown in Fig. 1, and it is desired to open the bed, the operator will grasp the sofa back frame 43 by inserting fingers of one hand in the opening 54 and pull forwardly. This force will initially swing the sofa back 41 and frame 43 upwardly and forwardly, causing section 37 to move forward until it strikes the back of the seat, and cause the upper end of the sofa-back frame 43 to clear stop 53 and swinging on hinges 42 the back will operate the legs 44 on pivots 45 under the control of links 47, into position to support the bed and until the pin 51 on legs 44 strikes the upper end of the slots 50. Thereafter, the forward swing of the legs will cause them to lock the sofa back frame against movement relatively to the foot section 37 of the bed. Continued forward pull upon the frame 43 will cause the seat frame to turn the seat around pivots 26. Such pull will be continued until the studs 27 seat in the lower ends of slots 29 and studs 26 have been operated upwardly to the upper ends of the slots 30, at which time the seat will be overturned and all of the bed sections will be aligned and in operative positions, as illustrated in Fig. 5. The operator will then lower the bed until the legs 44 rest on the floor to support the foot of the bed. This overturning of the seat will bring the bed sections 34 and 36 into operative position under the control of the springs 68. During this operation, the base board 63 will be swung rearwardly to a point to the rear of the seat, as illustrated in Fig. 5, the springs 65 causing the board to initially follow the turning movement of the seat frame. The foot board 55 will then be

swung upwardly to lift it off the mattress and such shift will cause it to operate the locking plates 59 through links 61 to engage studs 62 on the bed section 35, so that sections 35 and 37 will be locked against relative movement. Springs 58 will cross the dead center and serve to hold foot board 55 raised and in position to secure the locking plates 59 in operative position. To close the bed, the foot board 55 will first be swung downwardly to clamp the mattress and bed clothes on the bed and release the locking plates 59. Then the operator can grasp the sofa back and operate it reversely to the direction in which it is operated in opening the bed, which will cause the seat to be reversely turned and the bed sections to pass into folded position illustrated in Fig. 1. 75 80

The invention exemplifies a sofa bed, which comprises an overturning seat, a bed section connected to the seat and another section which is normally disposed in the rear of the sofa back and which, by a substantial single continuous shift, may be operated from closed to open position and vice versa.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a sofa bed, the combination of a sofa frame, a seat frame pivoted in said sofa frame so it can be overturned, a sofa back, a bed frame comprising a section fixedly secured to the underside of the seat frame and a section pivoted to said sofa back and to the section fixed to the seat frame, foldable into vertical position at the rear of the sofa back, and a stop for the front of the sofa back, the back being movable to clear the stop by pivotal movement relatively to the bed section to which it is pivoted. 100 105 110

2. In a sofa bed, the combination of a sofa frame, a seat-frame pivoted in said sofa-frame so it can be overturned, a bed frame composed of pivotally connected sections, a sofa back, the bed frame comprising, when 115 closed, a section fixedly secured to the underside of the seat and a vertical section at the rear of the seat-frame and in the rear of the sofa back, means for locking said sections together, and a spring pressed foot 120 board operatively connected to said locking means.

means.

3. In a sofa bed, the combination of a sofa frame, a bed-frame formed of foldably connected sections, and a pivotal connection between the frames comprising a pair of pivot studs and a plate having intersecting arcuate slots therein for the studs respectively, 125

- formed so the studs will be caused to successively act as a stationary fulcrum for the bed, the upper ends of the plates being open for the insertion and removal of the studs.
5. 4. In a sofa bed, the combination of a sofa frame, a bed frame formed of foldably connected sections and a pivotal connection between the frames comprising a pair of pivot studs and a plate having intersecting slots

therein for the studs respectively, formed so the studs will be caused to successively act as a stationary fulcrum for the bed, the upper ends of the plates being open for the insertion and removal of the studs and having extensions for holding the studs when the bed is open or closed.

JULIUS J. GRUENFELD, Jr.
